United States Patent Office.

BENJAMIN F. WILLIAMSON, OF FRANKLIN COUNTY, OHIO.

Letters Patent No. 71,672, dated December 3, 1867.

IMPROVEMENT IN SCROLL-SAW MILLS.

The Schedule referred to in these Letters Patent and making part of the same.

TO ALL WHOM IT MAY CONCERN:

Be it known that I, BENJAMIN F. WILLIAMSON, of the county of Franklin, and State of Ohio, have invented a new and useful Improvement on Frames or Tables for Scroll-Saws, to be used for sawing the face and falling-moulds for stairways, and other similar uses; and I do hereby declare that the following is a full, clear, and exact description of the construction and operation of the same, reference being had to the annexed drawings, making a part of this specification, in which—

Figure 1 is a perspective view of the whole frame.

Figure 2 is a separate view of the plate or cap used for cutting or sawing the falling-moulds, and

Figure 3 shows an end view of the latter.

To enable others skilled in the art to make and use my invention, I will proceed to describe its construction and operation.

A is a centre-post or pillar, on which is turned or operated the table or platform D, and through which passes the rod for driving the saw. B B are adjustable legs for raising or lowering the table or platform, by means of arms, c c, one end of the legs being attached to the table by means of hinges, or their equivalent, the lower end resting on the floor, with rollers so attached as to allow the table D to revolve at the pleasure of the workman. The arms or braces c c hold the legs B B in their proper position. D is the platform or table, which is caused to revolve on the centre-post A, and on which are sawed the face-moulds. E is a stop for holding the piece while being sawed, and for guiding the table D. F is the stock for admitting or steadyng the saw, such as is commonly used on scroll-frames. Fig. 2 is a small plate or heading, to be used on the centre-post A in lieu of the table D, when sawing falling-moulds.

What I claim as my invention, and desire to secure by Letters Patent, is—

The inclined and adjustable revolving platform or table D, constructed to operate substantially as described, and for the purpose set forth.

I also claim, in combination with the post A, the plate or heading I, constructed to operate substantially as and for the purpose set forth.

B. F. WILLIAMSON.
